UNITED STATES PATENT OFFICE.

HENRY E. CURTIS, OF SAN JOSE, CALIFORNIA, ASSIGNOR OF ONE-THIRD TO FRANK P. SCHEMEL, OF SAN JOSE, CALIFORNIA.

CARBURETER.

1,244,428.

Specification of Letters Patent. Patented Oct. 23, 1917.

Application filed February 7, 1916. Serial No. 76,787.

To all whom it may concern:

Be it known that I, HENRY E. CURTIS, a citizen of the United States, and resident of San Jose, in the county of Santa Clara and State of California, have invented certain new and useful Improvements in Carbureters, of which the following is a specification.

My invention relates to carbureters, and particularly to the means for regulating the fuel and air mixture in the same, reference being made to my co-pending application Serial No. 1,00,363, filed May 27, 1916.

The principal object of my invention is to provide means for automatically regulating the inflow of air into the mixing chamber of the carbureter so that the quantity of air drawn in will at all times be in proper proportion to the amount of fuel being used, and to provide a means of the nature specified that will be simple, compact, efficient, and cheap to manufacture.

With the above and other objects in view, the invention consists in the novel and useful formation, construction, combination and relative arrangement of parts as herein-after described, and illustrated in the accompanying drawings, in which—

Figure 1 shows a sectional view of a carbureter embodying my invention.

Fig. 2 shows a sectional view on line A—A of Fig. 1.

Similar characters of reference refer to similar parts throughout the several views. Referring now more particularly to the drawings, 1 indicates the float chamber of a carbureter, 2 the inner wall of said chamber, 3 the float, and 4 the liquid fuel in said chamber. At 5 is indicated the mixing chamber provided with a throttle valve 6. Mixing chamber 5 is shown cylindrical in shape and is a continuation of primary air chamber 7, said air chamber 7 being formed of the inner wall 2 of float chamber 1. A shoulder 8 is formed in the inner surface of wall 2 as shown and for the purpose herein-after set forth. At 9 is shown a spraying tube concentrically and axially positioned in said primary air chamber 7, the same being held in position by webs 10 preferably cast as an integral part of inner wall 2. Chamber 11 with its outer end closed by plug 12 and connected to float chamber 1 by con-

duits 13, provides a means by which fuel may be drawn from float chamber 1 through spraying tube 9 to the carbureting chamber of the carbureter. At 14 are shown air inlet ports to the mixing chamber 5.

At 15 I show a true Venturi tube slidably positioned in primary air chamber 7 in the following manner and having the following characteristics. The lowermost portion of the tube has an inner surface 16 in the form of a short truncated cone joined to the lower and smaller end of a comparatively longer truncated cone 17 by a short throat-piece 18. The outer surface of the lower portion of said Venturi tube 15 is of such a form and size as to slide easily in the lower portion of secondary air chamber 7, and is provided with a flange 20 of the proper size and form to engage shoulder 8 in wall 2. The outer surface of the upper portion of tube 15 is of the proper size and form to slide easily in chamber 7. A large proportion of the exterior of the wall of cone 17 is cut away to form air passage 21 and to reduce the weight of said Venturi tube 15. A plurality of orifices are shown at 22 so positioned in tube 15 as to permit the passage of air through openings 14 to mixing chamber 5 when tube 15 is advanced a distance. At 23 are shown a plurality of angularly positioned orifices in tube 15 connecting mixing chamber 5 with air passage 21.

When this carbureter is in position and in full operation its action is as follows:

Assuming that the engine is running under a light load, a comparatively small amount of fuel is being used and the proper amount of air is being drawn in through air chamber 7 and throat-piece 18 because Venturi tube 15 is in a retracted position and the discharge end 24 of spraying tube 9 is thereby advanced into cone 17 and no air is being drawn through ports 14.

If now the engine load is increased and the throttle valve 6 opened wide and an increased amount of air and liquid fuel is drawn into the mixing chamber 5 the following result is effected. The increased velocity of the air drawn in from chamber 7 through throat-piece 18 and the suction of air through orifices 22 and 23 causes Venturi tube 15 to advance to a position, say, as

indicated in dotted lines at 25, the discharge end 24 of spraying tube 9 being now positioned in approximately the center of throat-piece 18. Orifices 22 now permit air 5 to be drawn in through openings 14, and the increased velocity of air passing through throat-piece 18 draws an increased amount of liquid fuel from the discharge end of spraying tube 9, the increased velocity of 10 the air in said throat-piece 18 being due, of course, to the contracted space relative to the cones 16 and 17.

It may now be seen that the action of my 15 improved carbureter is entirely automatic, as the position of Venturi tube 15 depends entirely upon the pressure within the mixing chamber 5. When the engine load is heavy and the fluid pressure light the tube 20 15 is advanced as shown, a large amount of air is drawn into mixing chamber 5 and a proportionally large amount of liquid fuel is drawn from float chamber 1. As the engine load lightens the diminished suction of air permits tube 15 to recede thus diminishing the suction of liquid fuel from 25 spraying tube 9.

By fitting Venturi tube 15 into position as hereinbefore described, with flange 20 fitting snugly against wall 2 and the outer 30 surface of the lowermost portion of Venturi 15 also fitting snugly against wall 2 an air cushion is provided between flange 20 and shoulder 8 and I thereby obtain the effect of a dash-pot, and this is desirable as it 35 provides for a gradual movement of Venturi tube 15 in either direction according to the necessities of the engine, and thus provides for the exact proportioning of the liquid fuel and air mixture during any and all 40 positions of the throttle valve. Tube 15 should be made of a suitable light material, preferably cast aluminum, and therefore is exceedingly sensitive to changes in engine loads and speeds and a steadyng means is 45 necessary to prevent chattering or fluttering of the same. The air cushion provided for in the manner above described provides a perfect steadyng means for the tube, the term "snugly" being used to indicate that 50 tube 15 fits "closely but comfortably" within wall 2, a space being shown in the drawing between flange 20 and wall 2 and the lower portion of the tube and wall 2 to indicate that a tight fit is not desired and that 55 air can pass therethrough. Of course it is understood that the degree of snugness used depends upon the weight of tube 15 and this is determined mainly by the material of which it is made. While I have 60 herein shown and described one form of dash-pot it is, of course, conceivable that other forms may be devised for the purpose set forth but it is considered that the means shown and described is the most desirable.

85 While I have herein described and shown

one particular form of construction of my improved carbureter, it is understood that changes in form and construction and minor details may be made within the scope of the appended claims.

Having thus described my invention, what I claim as new and desire to secure by Letters Patent, is,—

1. The combination of a carbureter body and a fluid-pressure-controlled Venturi tube 70 slidably mounted therein, said tube being provided with an air passage on the exterior thereof and a plurality of upwardly and inwardly directed perforations connecting said air passage with the interior of said 80 tube, and means for steadyng the movements of said tube.

2. The combination of a carbureter body provided with compensating air inlet ports, and a fluid-pressure-controlled Venturi tube 85 slidably mounted therein, said tube having a passage formed in the exterior thereof, a plurality of perforations formed therein connecting said passage with the interior 90 of said tube, and a plurality of perforations formed therein connecting the exterior of said tube above said passage with the interior thereof, said passage and said last 95 mentioned perforations being adapted to communicate with said inlet ports when said tube is advanced.

3. The combination of a carbureter body having a shoulder formed in the inner wall thereof and a perforated fluid-pressure-controlled Venturi tube slidably mounted therein and provided with an air passage on the exterior thereof and a flange adapted to cooperate with said shoulder and thereby provide a dash-pot action for said tube, said 100 perforations being angularly positioned 105 with relation to a diametrical plane passing through said tube and connecting said passage with the interior of said tube, and a plurality of inlet ports in the upper portion of said carbureter body adapted to communicate with said passage when said tube is advanced.

4. The combination of a carbureter body having a shoulder formed in the inner wall thereof and a perforated fluid-pressure-controlled Venturi tube slidably mounted therein and provided with an air passage on the exterior thereof and a flange adapted to cooperate with said shoulder and thereby provide a dash-pot action for said tube, said 110 115 perforations being angularly positioned with relation to a diametrical plane passing through said tube, a plurality of said perforations connecting said passage with the interior of said tube and a plurality of said 120 perforations connecting the outer surface of said tube above said passage with the interior of said tube, and a plurality of inlet ports in the upper portion of said carbureter body adapted to communicate with said 125 130

last mentioned perforations and said passage when said tube is advanced.

5. The combination of a carbureter body provided with compensating air inlet ports, 5 and a perforated fluid-pressure-controlled Venturi tube slidably mounted therein, said tube being provided with a plurality of upwardly and inwardly directed perforations and having a range of movement that places 10 said perforations in communication with said inlet ports when said tube is advanced and closes said ports when said tube is retracted.

6. In a carbureter, the combination of a carbureter body provided with inlet ports in the upper portion thereof and having a shoulder formed in the inner wall thereof, a float chamber, a mixing chamber and a spraying tube, means for permitting the 20 passage of liquid from said float chamber to said mixing chamber through said spraying tube, and a perforated fluid-pressure-controlled Venturi tube provided with a carbureting chamber slidably mounted in said carbureter body and axially positioned with 25 relation to said spraying tube and with a range of movement that places said perforations in communication with said inlet ports and the discharge end of said spraying 30 tube in the throat portion of said Venturi tube when said tube is advanced and closes said inlet ports and places the discharge end of said spraying tube in said carbureting chamber when said Venturi tube is retracted, thereby automatically proportioning 35 the flow of fuel to the flow of air, said Venturi tube having an annular flange formed thereon adapted to engage said shoulder and thereby provide a dash-pot 40 action for said tube.

7. The combination of a carbureter body provided with compensating air inlet ports, and a fluid-pressure-controlled Venturi tube slidably mounted therein, said tube having 45 an air passage formed on the exterior thereof and a plurality of upwardly and inwardly directed perforations formed therein connecting said passage with the interior of said tube, said passage being adapted to

communicate with said inlet ports when 50 said tube is advanced.

8. The combination of a carbureter body provided with compensating air inlet ports, and a perforated fluid-pressure-controlled Venturi tube slidably mounted therein, said tube being provided with a plurality of upwardly and inwardly directed perforations and having a range of movement that places 55 said perforations in communication with said inlet ports when said tube is advanced 60 and closes said ports when said tube is retracted, and means for steadyng the movements of said tube.

9. The combination of a carbureter body provided with compensating air inlet ports, 65 and a fluid-pressure-controlled Venturi tube slidably mounted therein, said tube having a passage formed in the exterior thereof, a plurality of perforations formed therein connecting said passage with the interior 70 of said tube, and a plurality of perforations formed therein connecting the exterior 75 of said tube above said passage with the interior thereof, said passage and said last mentioned perforations being adapted to communicate with said inlet ports when said tube is advanced, and means for steadyng the movements of said tube.

10. The combination of a carbureter body provided with compensating air inlet ports, 80 and a fluid-pressure-controlled Venturi tube slidably mounted therein, said tube having a passage formed on the exterior thereof, a plurality of upwardly and inwardly directed perforations connecting said passage 85 with the interior of said tube, and a plurality of upwardly and inwardly directed perforations formed therein connecting the exterior of said tube above said passage with the interior thereof, said passage and said 90 last mentioned perforations being adapted to communicate with said inlet ports when said tube is advanced, and means for steadyng the movement of said tube.

In testimony whereof I have hereunto 95 affixed my signature this 2nd day of February, 1916.

HENRY E. CURTIS.
